Ibaragi, Japan, assignors to Matsushita Electric Industrial Co., Ltd., Osaka, Japan

Filed Apr. 5, 1971, Ser. No. 131,592

Claims priority, application Japan Oct. 6, 1970

Term of patent 14 years

Int. Cl. D14—03

U.S. Cl. D56—4

FIG. 1

FIG. 2

FIG. 3

FIG. 1 is a top, front and right side perspective view of a combined radio receiver, tape recorder and television receiver showing our new design.

FIG. 2 is a bottom, rear and left side perspective view thereof, and

FIG. 3 is a top, front and right side perspective view thereof showing the television receiver in using position and lid of the tape recorder in opened position.

Portions of the drawing figures have been stippled to indicate contrast in appearance.

We claim:

The ornamental design for a combined radio receiver, tape recorder and television receiver, as shown and described.
